CLAIM

The ornamental design for a beverage container as shown and described.

DESCRIPTION

FIG. 1 is a top, front, right side isometric view of a beverage container showing my new design;

FIG. 2 is a bottom, front, right side isometric view thereof;

FIG. 3 is a front elevation view thereof;

FIG. 4 is a rear elevation view thereof;

FIG. 5 is a left side elevation view thereof, the right side elevation being a mirror image of the left side elevation;

FIG. 6 is a top plan view thereof; and,

FIG. 7 is a bottom plan view thereof.

The broken lines in the drawings depict portions of the beverage container that form no part of the claimed design.

1 Claim, 7 Drawing Sheets
